UNITED STATES PATENT OFFICE.

THOMAS F. GILCREST, OF DES MOINES, IOWA.

RAILROAD-TIE.

No. 902,287.

Specification of Letters Patent.

Patented Oct. 27, 1908.

Application filed August 31, 1907. Serial No. 390,972.

To all whom it may concern:

Be it known that I, THOMAS F. GILCREST, a citizen of the United States, residing at Des Moines, in the county of Polk and State 5 of Iowa, have invented a new and useful Railroad-Tie, of which the following is a specification.

This invention has reference to improvements in railroad ties, and is designed to produce a composite tie of cement and metal, the metal forming a bond for the cement and also constituting a broad bearing for the rails, while the cement protects the metal and forms an extended support therefor between the metal and the ground.

The invention consists essentially of a tie of usual shape the body of which is composed of cement, lengthwise through which extend webs of metal suitably spaced and locked 20 and constituting the bonds for holding the cement together and preventing it crumbling or disintegrating under shocks or blows.

In accordance with the present invention there are provided two angle plates with 25 their sides parallel to each other and spaced apart and their angle extensions projecting in opposite directions and constituting the major portion of the top or bearing face of the tie. Adjacent to but spaced from the 30 parallel portions of the two angle irons are metal strips locked to the angle irons and constituting locking members for the cement body of the tie. Fast to the top of the bearing faces of the angle irons are clips by means 35 of which the rails are securely clamped to the ties.

The invention will be fully understood from the following detailed description, taken in connection with the accompanying drawings forming part of this specification, in which,

Figure 1 is an elevation of the improved tie, with a portion shown in section and with the rails in position, the latter also being 45 shown in section; Fig. 2 is a top plan view of a rail and so much of a tie as is contiguous thereto; Fig. 3 is a longitudinal transverse section of a portion of a tie in the line of the spacing bolts; and Fig. 4 is a cross section 50 of a tie adjacent to a rail.

Referring to the drawings, there are shown two angle irons which are composed of a web 1 and an angle extension 2. The webs 1 are arranged parallel one to the other and connected by bolts 3, but surrounding the said bolts are spacing sleeves 4 so that the body

portions of the webs 1 are spaced apart a distance equal to the length of the sleeves 4. The angle portions 2 of the angle irons form the top of the tie and project in opposite directions and reach points coincident with the sides of the tie.

On the outer side of each web portion 1 of the angle irons there is a metallic strip 5 through which the bolts 3 extend and on these bolts between the web portions 1 and the strips 5 are spacing sleeves 6. The strips 5 are narrower and thinner than the web portions 1 and the bolts 3 serve to lock together both the webs 1 and strips 5, there being left between the strips 5 and the outer faces of the webs 1 spaces corresponding to the length of the sleeves 6.

When the metallic structure thus far described is properly assembled a cement body 7 is molded around the same so as to fill all the spaces, and in cross section the cement body is preferably rectangular although not necessarily so. When the cement body is suitably formed about the metallic parts the upper surfaces of the angle portions 2 are exposed while the cement fills the space between the webs 1 and up to the top surface of the angle portions 2. The cement body 7 is so applied to the metallic parts as to completely embed the same except that at certain portions there are provided recesses 8 in the sides of the cement body.

The tie is of any suitable length, and on the faces of the angle portions 2 are laid the usual traffic rails 9. These rails are held in place by clips 10 resting upon the upper faces of the angle extensions 2 and provided with lips 11 overriding the flanges of the rails and serving to bind the same firmly to the ties. These clips are held in place by bolts 12, the heads 13 of which engage the under faces of the angle extensions 2 at the points where the recesses 8 are formed in the cement body 7, and the nuts 14 of these bolts bear upon the top of the clips 10 and so bind the latter firmly to the angle extensions 2. While not so shown, it is to be understood that any appropriate form of nut lock may be applied to the bolts 12, to prevent the accidental displacement of the nuts 14 therefrom.

The sleeves 6 before referred to may be either simple sleeves or the bolts 3 may be formed of rods threaded at each end to a sufficient distance and the sleeves 6 may be in the form of nuts applied to the bolts and

clamping the webs 1 firmly together, while the strips 5 are clamped to the nuts 6 by means of other appropriate nuts. Since the nuts of the bolts 3 are embedded in the cement body no nut locks are necessary.

It will be observed that the angle irons, which are extended throughout the length of the tie, constitute a broad bearing surface for the rails, so that the weight of the rails, 10 or of cars passing over the rails, is distributed over a large area of the cement body, while at the same time the webs of these angle irons act as reinforcements for the cement body of the ties. Furthermore, the body of 15 cement adjacent to the outer faces of the webs is further reinforced by the strips 5 so that the cement is not liable to break away from the webs 1. Because of this construction the cement body has little tendency to 20 disintegrate or crack, and, even if cracked to a certain extent, to fall away from the metallic parts and so decrease the efficiency of the tie.

The rails are held in their spaced position 25 by the angle irons 1-2, and any tendency of these angle irons to expand and contract under the action of heat is counteracted by the binding action of the cement body.

The composite ties approximate in size and 30 shape the commonly used wooden ties and are particularly adapted to replace wooden ties and coöperate with equal facility with the road ballast usually employed.

Instead of using bolts 12 to secure the 35 clips 10 to the angle irons 2, I may use rivets, as will be readily understood. The clips 10, while primarily intended to secure the rails to the tie, also serve to give material additional bonding strength to the angle irons.

40 I claim:—

1. A composite tie for railways composed of spaced angle irons and a cement body completely embedding the webs of the angle irons with the angle extensions of said angle

irons at the surface of the tie and projecting 45 oppositely and together with the cement body between the webs constituting the rail-receiving face of the tie.

2. A composite tie for railways composed of a cement body and spaced angle irons 50 having their webs adjacent and the angle extensions projecting oppositely, the cement body completely embedding the webs of the angle irons and extending between them and level with the surface of the angle extensions, 55 and means also embedded in the cement body for holding the angle irons in spaced relation.

3. A composite tie for railroads, composed of a body of cement, spaced angle irons having web portions embedded in the body of the tie and their angle extensions constituting the rail-supporting face of the tie, bolts extending through the webs of the angle irons within the cement body, spacing sleeves 65 surrounding the bolts and holding the webs apart, metallic strips parallel with the outer faces of the webs and carried by the bolts, and spacing means between the strips and the contiguous faces of the webs. 70

4. A composite tie for railroads composed of a body of cement, spaced angle irons having the web portions embedded in the body of the tie with the angle extensions oppositely projecting and constituting the rail- 75 supporting face of the tie, longitudinally-disposed strips adjacent to the outer faces of the webs and also embedded in the cement body, and means for connecting the webs together and to the strips. 80

In testimony that I claim the foregoing as my own, I have hereto affixed my signature in the presence of two witnesses.

THOMAS F. GILCREST.

Witnesses:

Wm. MONTGOMERY,
BERTIE LYNN.
